THERMAL OVERLOAD RELAY

Alexander R. Norden, New York, N.Y., assignor to Federal Pacific Electric Company, a corporation of Delaware

Filed Nov. 9, 1960, Ser. No. 68,233
20 Claims. (Cl. 200—122)

This invention relates generally to an overload relay and, more particularly, to an overload relay provided with ambient temperature compensation for electric motor control.

One important object of the present invention is the provision of an overload relay for electric motor control having ambient temperature compensation in which such compensation is immune from all mechanical stresses of the contact operating mechanism at its point of operation. This arrangement represents an important desideratum since the ambient temperature compensation is isolated from the contact operating mechanism and is thus not affected by variations resulting from extraneous mechanical stresses that may be present in the contact operating mechanism. Pursuant to the present invention, the contact operating mechanism is of the toggle type and the ambient temperature compensating bimetal is disengaged from the toggle mechanism at the point of overtoggling, thus rendering such bimetal immune from mechanical stresses in such mechanism at overtoggle.

Another important object of the present invention is the provision of a reset control in an overload relay of the aforesaid character to provide a reset time adjustment which is dependent of ambient temperature variations. In this manner once the reset time is adjusted it will not be altered by ambient temperature changes. The reset time adjustment mechanism is physically displaced from, and operatively coordinated with, the ambient temperature compensating bimetal to achieve the aforesaid objectives.

Another object of the present invention is the provision of an overload relay of the aforesaid character having improved provision for selective automatic or manual reset control.

Yet another object of the present invention is the provision of an overload relay for motor control of the aforesaid character, which is of generally improved design and construction, economical to mass produce, efficient, reliable and foolproof in operation, and which is eminently suitable for carrying out its intended purposes.

Other objects, features and advantages of the present invention will become apparent as the description thereof proceeds when considered in connection with the accompanying illustrative drawings.

In the drawings:

FIG. 1 is a side elevational view of an overload relay formed in accordance with the present invention, the relay being shown with a cover plate removed and in the closed automatic reset condition;

FIG. 2 is a top view of the overload relay illustrating the selective reset control and the top portion of the reset plunger;

FIG. 3 is an enlarged sectional view taken on the line 3—3 of FIG. 1;

FIG. 4 is a view similar to FIG. 3 showing the overload relay in the manual reset tripped position;

FIG. 5 is a fragmentary side elevational view similar to FIG. 1 showing the overload relay in the manual reset closed position;

FIG. 6 is a fragmentary view showing the position of the reset plunger and toggle mechanism in the manual reset closed position;

2

FIG. 7 is a perspective view of the toggle mechanism with parts including the main operating bimetal and its companion operating link removed;

FIG. 8 is a perspective view similar to FIG. 7 showing the complete toggle mechanism and the main operating bimetal; and

FIG. 9 is a sectional view taken on the line 9—9 of FIG. 1.

Referring to the drawings, and more particularly to FIGS. 1—4, there is shown an overload relay 10 for electric motor control having ambient temperature compensation. The relay 10 comprises a housing 12 which encases the operating mechanism to be described, said housing having a center body part 14 and outer cover plates 16 and 18 suitably secured to said body part. The operating mechanism comprises a main operating bimetal 20 disposed in compartment 22 defined by the insulating wall 24, said bimetal 20 being secured at one end to the leg 26 (see FIG. 8) of the mounting bracket 28 which is secured to wall 24. Extending through the leg 26 and bimetal 20 is a screw 30 which engages the wall 28' of bracket 28 and provides a tripping level calibration adjustment. The free end 31 of bimetal 20 defines a reduced width laterally offset actuating finger 32 which projects through a companion slot 34 of link 36 for actuating the latter. Disposed adjacent to the bimetal 20 is a heater 36 therefor comprising a series of convolutions of wire, the terminals of which are adapted to be connected in series with the load or motor so that the bimetal will be operatively responsive to thermal overloads in the motor. An insulating plate 38 is suitably secured to the heater at the side opposite to the main bimetal.

The wall 24 is slotted at 40 to slidably receive the link 34. Mounted on the wall 24 and extending in compartment 42 is a support 44 which mounts the operating member 46 and toggle link 48 at one side of the insulator plates 50 and the ambient temperature compensating bimetal 52 at the opposite side of said plates. The toggle link 48 is in the form of a narrow conductive strip having a cutout 54 adjacent the fixed end thereof to increase its sensitivity, said link carrying a contact 56 and a control in the form of a screw 58, fabricated from insulating material, for reset time adjustment as will be described in detail hereinafter. With reference to FIGS. 7 and 8, the free end of link 48 is slotted as indicated at 60 for connection with the T-shaped end portion 62 of the U-shaped toggle spring 64. The opposite end of the spring 64 is slotted at 66 for the reception of the flange 68 of the operating member 46 to thereby provide an operative connection between the member 46 and said spring. The operating member 46 is in the form of an open frame having laterally spaced side members 70, the free end 72 thereof being narrowed and in operative engagement with the portion 74 of link 34. Thus the deflection of bimetal 20 is operative to correspondingly deflect the member 46 through link 34 and to actuate the toggle mechanism, as will be described in detail. The toggle link 48 at its free end is provided with a laterally projecting finger or latch 76 for coaction with the reset plunger 78.

Disposed along one face of the compensating bimetal 52 is a conductive strip 79 having a contact 80 adjacent the free end of the bimetal for coaction with its companion contact 56. The compensating bimetal 52 and companion strip 79 are apertured as indicated at 82 to receive the reset time adjusting screw 58 with clearance. It will be understood that the terminals 84 and 84' are electrically connected respectively to the contacts 56 and 80 and the circuit therebetween is closed on contact closing and opened on contact separation. As shown in FIGS.

3 and 4, the cover plate 16 is recessed at 86 to provide the requisite clearance for the head of screw 58.

In operation, with the overload relay conditioned for automatic resetting as shown in FIGS. 1 and 2, the contacts 56 and 80 will be closed on normal operation. On predetermined thermal overloads the heater 36 will cause the upward deflection of bimetal 20 and operating member 46 through link 34 carrying the end 66 of the spring 64 in said direction. The opposite end of the spring 64 is restrained so that on predetermined actuation of the end 66 of the spring the latter will overtoggle and carry link 48 downwardly to concomitantly move contact 56 away from its companion contact 80 and open the circuit. This downward movement of link 48 will continue until the head of screw 58 carried by said link engages the bimetal 52 which serves as a limit stop for the overtoggle of the linkage. On cooling of the main bimetal 20 in accordance with the adjusted position of the screw 58 the linkage will reset to close the circuit. The terminal point of overtoggle is under the control of screw 58 which is adjustable to adjust the circuit reset time. Thus the greater the adjusted spacing between the head of screw 58 and the bimetal 52 the longer the reset time as a consequence of the longer stroke or travel required for resetting the toggle after tripping. Thus the terminal tripping point of the toggle is determined by the adjusted position of screw 58.

It will be noted that the reset time adjustment 58 is independent of ambient temperature variations so that once the reset time is adjusted it will not be altered by changes in ambient temperature. This adjustment, while physically displaced from the bimetal 52, is operatively coordinated therewith, the screw 58 cooperating with said bimetal to determine the terminal tripping point of the toggle mechanism as described above. At the dead-center point of the toggle, the bimetal 52 is about to separate from toggle link 48. At that moment, the bimetal 52 is immune to all mechanical stresses within the toggle mechanism and therefore the overtoggle point is not affected by variations in mechanical stresses present in such toggle mechanism. Referring to FIG. 3, on an ambient temperature rise both bimetals 20 and 52 will deflect in the same direction, i.e., an upward direction and said bimetals are physically coordinated so that a predetermined thermal overload will govern tripping of the toggle mechanism independent of ambient temperature variations. Thus ambient temperature variations will have no effect on the overload tripping level as the ambient temperature deflection of the main bimetal will be neutralized by the deflection of the compensating bimetal which governs the position of the contacts 56, 80.

It has been shown that bimetal 52 and toggle element 48 cooperate in both over-toggled configurations of the relay, that is, both when the contacts are closed and when the contacts are open. When the contacts are closed the coaction is direct in that contact 56 on toggle element 48 presses against contact 80 on bimetal 48. When the contacts are open, element 48 is mechanically connected to bimetal 52 through screw 58. During the process of overtoggling, element 48 is free of constraining connection to bimetal 52, the range of free or lost motion being established by the adjusted spacing between the head of screw 58 and bimetal 52 as mentioned above. The element 48 of the toggle and the bimetal 52, which cooperate with each other mechanically only at the ends of the range of motion of toggle element 48, are thus interconnected by means providing lost-motion coupling therebetween.

The reset plunger 78 is of arcuate configuration and is preferably molded of a suitable insulating material, said plunger being slidably mounted in a complementary slot 88 of the housing 12. The slot 88 extends through the housing at one end as indicated at 88' for the extension therethrough of the indicator portion 90 of the plunger. The lower end of the plunger has a laterally projecting

portion 92 provided with a latch portion 92' which is operatively coupled with latch 76 of the toggle link 48 under the conditions to be described. Below the portion 90 of the plunger there is provided a laterally projecting part 94 which is slotted at 96 for the reception of the arm 98 of the control spring 100.

The spring 100 is provided with a circular bearing portion 102 which is seated on stud 104 integral with the housing (see FIG. 9) and a finger portion 106 which extends outwardly of the housing through the slotted portion 108 thereof. Projecting into the slotted portion 108 is a detent 110 and portion 106 is selectively positionable on either side of said detent. To shift portion 106 to an opposite position to alter the operation of the relay said portion is manually depressed laterally to the broken line position 106' shown in FIG. 9 to bypass the detent 110 and pivoted about stud 104 and released to engage in such opposite position against the detent. It will be understood that the housing is cutaway as indicated at 112 to receive spring 100 and its companion part 94 with the requisite operating clearances. The portion 106 is laterally offset with respect to the spring 100 as best shown in FIG. 9, said spring being formed by suitably bending a length of spring wire.

Referring to FIGS. 1-3, the portion 106 is shown in the automatic reset position in which the spring arm 98 is disposed against the wall 114 of the housing and the plunger 78 is retracted in the housing (FIG. 1). In this condition the latch portion 92' of the plunger is physically out of contact with latch 76 of the toggle mechanism which is free for the aforescribed normal overtoggling and resetting operation. Accordingly in the automatic reset position the plunger 78 is disposed out of operation with the toggle mechanism, which is free for automatic resetting subsequent to tripping on thermal overload, and thus exerts no control influence over such mechanism. In the opposite manual reset position of portion 106 (FIGS. 4-6) the arm 98 of the control spring biases the plunger in a direction outwardly of the housing and with the contacts and toggle mechanism closed the latch 76 of the toggle mechanism coacts with latch portion 92' to latch the plunger down, i.e. in retracted position. On tripping of the toggle mechanism on thermal overload the latch 76 releases latch portion 92' and the plunger is shifted to an extended position with respect to the housing as shown in broken lines in FIG. 5 under the influence of the aforesaid spring biasing. In this position the indicator portion 90 of the plunger is fully exposed to indicate the tripped condition of the relay. With reference to FIG. 4, it will be noted that in the manual reset tripped condition of the relay the portion 92 of the plunger blocks the latch 76 to block the automatic resetting of the toggle mechanism. Thus the mechanism must be manually reset which is accomplished by depressing the plunger at portion 90 slightly beyond latch 76 so that the latter may relatch the plunger in the position shown in FIGS. 5 and 6 and permit the resetting of the toggle mechanism. It will be noted that in the manual reset tripped position the spring arm 98 engages the wall 114' of the housing and shifts the plunger outwardly of the housing. Thus the control portion 106 provides a selective control for the relay which may be positioned for either automatic or manual reset with the plunger giving a visual indication of the tripped condition of the relay in the manual reset position of said portion 106.

Various additional modifications of the above embodiments of the invention will readily occur to those skilled in the art, and therefore the invention should be broadly construed in accordance with its full spirit and scope.

Having thus described my invention what I claim as new and desire to secure by Letters Patent is:

1. A thermal overload relay for an electric circuit, comprising a companion pair of separable contacts, operating mechanism therefor including toggle linkage and an operating device comprising a thermal element responsive to a

predetermined thermal overload to over-toggle said linkage and open said contacts, and an ambient temperature compensating thermal element separate from but cooperating with said operating mechanism to control at least one over-toggle point of said linkage, said compensating element being physically separate from and separated from said operating mechanism at the instant following over-toggle of said linkage.

2. An overload relay in accordance with claim 1 where-in one of said contacts is carried by an element of said toggle linkage and the other of said contacts is carried by said compensating element at a point thereof that moves with variations in ambient temperature, said contacts when closed constituting one of the over-toggle control points of said linkage.

3. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal having relatively fixed and movable portions, said compensating bimetal being physically displaced from said operating bimetal and operatively coordinated therewith, said compensating bimetal physically separating from said operating mechanism at the point of contact opening of said linkage, said toggle linkage comprising an operating member operatively connected to said operating bimetal, a toggle link carrying one of said contacts and a toggle spring interposed between said operating member and toggle link for biasing the latter in the contact open and closed positions thereof, and the other contact being carried by said movable portion of said compensating bimetal, the latter restraining the movement of said linkage in the contact closed position thereof.

4. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal having an active portion cooperable with said operating mechanism, said compensating bimetal being physically displaced from said operating bimetal, said compensating bimetal physically separating from said operating mechanism at the point of contact opening over-toggle of said linkage, said bimetals being disposed at opposite sides of said toggle linkage and arranged to deflect in the same direction in response to ambient temperature variations, and a heater in heat transfer relation with said operating bimetal adapted to be connected in circuit with the load.

5. A thermal overload relay having ambient temperature compensation, comprising a companion pair of contacts, operating mechanism therefor including toggle linkage comprising a generally U-shaped toggle spring, a cantilever operating bimetal having a heater responsive to overloads in the load circuit for actuating said toggle linkage to open and close said contacts, said toggle spring biasing said contacts in said open and closed positions on over-toggling of said linkage, and a cantilever ambient temperature compensating bimetal disposed at the opposite side of said linkage to said operating bimetal, said compensating bimetal being arranged to deflect in the same direction as said operating bimetal and in physical coordination therewith in response to ambient temperature variations, said compensating bimetal restraining the movement of said linkage in the contact closed position thereof and physically separating from said linkage at the point of overtoggle thereof to open said contacts.

6. A thermal overload relay having ambient temperature compensation, comprising a companion pair of contacts, operating mechanism therefor including toggle linkage comprising a generally U-shaped toggle spring, a cantilever operating bimetal having a heater responsive to overloads in the load circuit for actuating said toggle

linkage to open and close said contacts, said toggle spring biasing said contacts in said open and closed positions on overtoggling of said linkage, and a cantilever ambient temperature compensating bimetal disposed at the opposite side of said linkage to said operating bimetal, said compensating bimetal being arranged to deflect in the same direction as said operating bimetal and in physical coordination therewith in response to ambient temperature variations, said compensating bimetal restraining the movement of said linkage in the contact closed position thereof and physically separating from said linkage at the point of overtoggle thereof to open said contacts, the latter being carried by said linkage and compensating bimetal, respectively, at the only point of physical co-ordination thereof in the contact-opening over-toggle operation of said linkage.

7. A thermal overload relay for an electric circuit, comprising a companion pair of separable contacts, operating mechanism therefor including toggle linkage and an operating member responsive to predetermined thermal overloads to overtoggle said linkage and open said contacts, and ambient temperature compensating means cooperable with said operating mechanism, said means physically separating from said operating mechanism on said over-toggle of said linkage in the contact-opening direction so that said means is substantially unaffected by mechanical stress variations in said mechanism, and a reset time control for said operating mechanism independent of ambient temperature variations.

8. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal cooperating with said operating mechanism in only one of the two over-toggle conditions of the toggle linkage, said compensating bimetal being physically displaced from said operating bimetal and operatively coordinated therewith, said compensating bimetal physically separating from said operating mechanism at the point of overtoggle of said linkage, and a reset time control for said operating mechanism physically displaced from, and operatively coordinated with, said compensating bimetal whereby said reset time control is unaffected by ambient temperature variations.

9. An overload relay having ambient temperature compensation, comprising a companion pair of separable contacts, operating mechanism therefor including toggle linkage and an operating bimetal responsive to pre-determined thermal overloads to over-toggle said linkage and open said contacts, and an ambient temperature compensating bimetal spaced physically from said operating bimetal and thermally co-ordinated therewith, said ambient temperature compensating bimetal having lost-motion connecting means to said toggle linkage effective to control the points of over-toggling thereof both when the contacts are closed and when the contacts are open, said lost-motion connection providing a reset time control for said operating mechanism whose reset time is unaffected by ambient temperature variations.

10. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal interposed in said operating mechanism, said compensating bimetal being physically displaced from said operating bimetal and operatively coordinated therewith, and a reset time control for said operating mechanism physically displaced from, and operatively coordinated with, said compensating bimetal whereby said reset time control is unaffected by ambient temperature variations, said reset time control comprising an adjustable stop carried by said toggle linkage, said stop engaging said compensating bi-

metal on contact opening overtoggle of said linkage to limit the contact opening movement thereof.

11. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal interposed in said operating mechanism, said compensating bimetal being physically displaced from said operating bimetal and operatively coordinated therewith, said toggle linkage comprising an operating member operatively connected to said operating bimetal, a toggle link carrying one of said contacts and a toggle spring interposed between said operating member and toggle link for biasing the latter in the contact open and closed positions thereof, and the other contact being carried by said compensating bimetal, the latter restraining the movement of said linkage in the contact closed position thereof, and a reset time control for said operating mechanism comprising an adjustable stop carried by said toggle link, said stop being physically displaced from, and operatively coordinated with, said compensating bimetal, said stop engaging said compensating bimetal on contact opening over-toggle of said linkage to determine the contact opening movement thereof.

12. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal interposed in said operating mechanism, said compensating bimetal being physically displaced from said operating bimetal and operatively coordinated therewith, said toggle linkage comprising an operating member operatively connected to said operating bimetal, a toggle link carrying one of said contacts and a toggle spring interposed between said operating member and toggle link for biasing the latter in the contact open and closed positions thereof, and the other contact being carried by said compensating bimetal, the latter restraining the movement of said linkage in the contact closed position thereof, and a reset time control for said operating mechanism comprising an adjustable stop carried by said toggle link, said stop being physically displaced from, and operatively coordinated with, said compensating bimetal, said stop engaging said compensating bimetal on contact opening over-toggle of said linkage to determine the contact opening movement thereof, said stop being constituted by an adjustable screw extending freely through an opening provided in said compensating bimetal, said screw having a head engageable with said compensating bimetal to determine the contact opening movement of said linkage, the clearance between said head and said compensating bimetal in the contact closed position of said linkage being adjustable to concomitantly adjust the reset time of said linkage subsequent to tripping.

13. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal interposed in said operating mechanism, said compensating bimetal being physically displaced from said operating bimetal and operatively coordinated therewith, said toggle linkage comprising an operating member operatively connected to said operating bimetal, a toggle link carrying one of said contacts and a toggle spring interposed between said operating member and toggle link for biasing the latter in the contact open and closed positions thereof, and the other contact being carried by said compensating bimetal, the latter restraining the movement of said linkage in the contact closed position thereof, and a reset time control for said operating mechanism comprising an ad-

justable stop carried by said toggle link, said stop being physically displaced from, and operatively coordinated with, said compensating bimetal, said stop engaging said compensating bimetal on contact opening overtoggle of said linkage to determine the contact opening movement thereof, said compensating bimetal physically separating from said linkage at the point of overtoggling on the tripping thereof.

14. A thermal overload relay having ambient temperature compensation, comprising a companion pair of contacts, operating mechanism therefor including toggle linkage comprising a generally U-shaped toggle spring, a cantilever operating bimetal having a heater responsive to overloads in the load circuit for actuating said toggle linkage to open and close said contacts, said toggle spring biasing said contacts in said open and closed positions on overtoggling of said linkage, and a cantilever ambient temperature compensating bimetal disposed at the opposite side of said linkage to said operating bimetal, said compensating bimetal being arranged to deflect in the same direction as said operating bimetal and in physical coordination therewith in response to ambient temperature variations, said compensating bimetal restraining the movement of said linkage in the contact closed position thereof and physically separating from said linkage at the point of overtoggle thereof to open said contacts, and a reset time control for said operating mechanism physically displaced from, and operatively coordinated with, said compensating bimetal whereby said reset time control is unaffected by ambient temperature variations.

15. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal interposed in said operating mechanism, said compensating bimetal being physically displaced from said operating bimetal and operatively coordinated therewith, said toggle linkage comprising an operating member operatively connected to said operating bimetal, a toggle link carrying one of said contacts and a toggle spring interposed between said operating member and toggle link for biasing the latter in the contact open and closed positions thereof, and the other contact being carried by said compensating bimetal, the latter restraining the movement of said linkage in the contact closed position thereof, and a reset time control for said operating mechanism comprising an adjustable stop carried by said toggle link, said stop being physically displaced from, and operatively coordinated with, said compensating bimetal, said stop engaging said compensating bimetal on contact opening over-toggle of said linkage to determine the contact opening movement thereof, and control means selectively providing for automatic or manual resetting of said linkage subsequent to overtoggling.

16. An overload relay having ambient temperature compensation, comprising a companion pair of separable contacts, operating mechanism therefor including toggle linkage and an operating bimetal responsive to predetermined thermal overloads to overtoggle said linkage and open said contacts, and an ambient temperature compensating bimetal cooperable with said operating mechanism, said compensating bimetal being physically displaced from said operating bimetal and operatively coordinated therewith, said compensating bimetal physically separating from said operating mechanism at the point of overtoggling of said linkage, and manual control means selectively providing for automatic and manual resetting of said linkage subsequent to overtoggling, said means comprising a reset plunger and a control member operatively coupled therewith for selecting the operation thereof, said plunger being operatively uncoupled from said linkage in the automatic reset position of said control member and being operatively connected to said linkage in the manual reset position of said control member, said

plunger in said latter position of said control member blocking the resetting of said linkage subsequent to over-toggling and being manually depressible out of the path of resetting movement of said linkage to clear the latter for resetting.

17. An overload relay having ambient temperature compensation, comprising a companion pair of separable contacts, operating mechanism therefor including toggle linkage and an operating bimetal responsive to predetermined thermal overloads to over-toggle said linkage and open said contacts, and an ambient temperature compensating bimetal interposed in said operating mechanism, said compensating bimetal being physically displaced from said operating bimetal and operatively coordinated therewith, said compensating bimetal physically separating from said operating mechanism at the point of over-toggle of said linkage, a reset control member selectively movable to automatic and manual reset positions, a reset plunger operatively connected to said control member for control thereby, said plunger and linkage having cooperating parts in latching engagement restraining said plunger in position in contact closed position of said linkage with said control member in said manual reset position, said plunger in said last mentioned position being biased into engagement with said linkage, the over-toggling thereof releasing said plunger under said biasing influence for movement to a tripped position in which said plunger blocks the resetting of said linkage, said plunger having an indicator portion at its outer end indicating the tripped condition of said linkage, said portion being manually depressible to clear said cooperating parts thereby permitting the resetting of said linkage and the relatch of said cooperating parts.

18. A thermal relay having an adjustable tripping point and ambient temperature compensation and having an adjustable reset time independent of tripping-point adjustment and ambient temperature variations, said relay including an active bimetal, load-current carrying means causing heating of said active bimetal in response to load current, and ambient temperature compensating bimetal, companion contacts, and an over-centering snap-acting device for opening and closing said contacts under control of said bimetals, both of said bimetals being mechanically coupled to said snap-acting device and being effective to control snap-action thereof both in the contact-opening direction and in the contact-closing direction, said active bimetal having an adjustment effective to control the current-level at which automatic opening of the contacts occurs, the mechanical coupling of one of said bimetals including a positive coupling to said snap-acting device effective only when said device is in its closed condition and including a positive coupling to said device effective only when said snap-acting device is in its open condition, said snap-acting device having a range of motion during its over-centering operation when it is free of restraint by both of said positive-acting coupling means, and means for adjusting the range of restraint-free operation of said device, for thereby controlling the reset time following an automatic contact-opening operation, reclosing of the contacts occurring automatically at the end of the reset time.

19. A thermal relay having an adjustable tripping point and ambient temperature compensation and having

an adjustable reset time independent of tripping-point adjustment and ambient temperature variations, said relay including an active bimetal, load-current carrying means causing heating of said active bimetal in response to load current, an ambient temperature compensating bimetal, companion contacts, and an over-centering snap-acting device for opening and closing said contacts under control of said bimetals, both of said bimetals being mechanically coupled to said snap-acting device and being effective to control snap-action thereof both in the contact-opening direction and in the contact-closing direction, said active bimetal having an adjustment effective to control the current-level at which automatic opening of the contacts occurs, the mechanical coupling of said compensating bimetal to said snap-acting device including means constraining said snap-acting device in the closed condition of the device and means constraining said device in the open condition of said device, and said snap-acting device having a range of motion during the snap action thereof when the device is free of constraint by both of said constraining means, one of said constraining means being adjustable for thereby controlling the reset time following an automatic over-centering operation in one direction, reverse operation of the contacts occurring automatically at the end of an adjustable reset time.

20. A thermal relay having an adjustable tripping point and ambient temperature compensation and having an adjustable reset time independent of tripping-point adjustment and ambient temperature variations, said relay including an active bimetal, load-current carrying means causing heating of said active bimetal in response to load current, an ambient temperature compensating bimetal, companion contacts, and an over-centering snap-acting device for opening and closing said contacts under control of said bimetals, both of said bimetals being mechanically coupled to said snap-acting device and being effective to control snap-action thereof both in the contact-opening direction and in the contact-closing direction, said active bimetal having an adjustment effective to control the current-level at which automatic opening of the contacts occurs, and said compensating bimetal having means providing mechanical coaction with said snap-acting devices only at the ends of a range of free and unconstrained relative motion between the compensating bimetal and the snap-acting device, said last named means including a device for adjusting said range of free motion for thereby controlling the reset time following an automatic contact-opening operation, reclosing of the contacts occurring automatically at the end of the reset time.
